UNITED STATES PATENT OFFICE.

ARTHUR H. PHILLIPS, OF HEMPSTEAD, NEW YORK, ASSIGNOR TO AMERICAN SALES BOOK COMPANY, LIMITED, OF TORONTO, CANADA, A CORPORATION OF CANADA.

MANIFOLDING SALES BOOK.

Application filed April 17, 1924. Serial No. 707,027.

This invention relates to salesbooks, and with respect to its more specific features, to salesbooks in which a plurality of copies may be made in a single book in a new and 5 improved manner.

A further object is to provide a book of the character described, in which carbons may be inserted from a free side of the book with assurance that the carbon sheet will 10 cover the entire record face of the under leaves.

A further object is to provide a book of the character described to be simple in manipulation, inexpensive in construction, and 15 which may be constructed to make any number of records desired from a single pad.

The invention accordingly comprises an article of manufacture possessing the features, properties, and the relation of elements which will be exemplified in the article hereinafter described and the scope of 20 the application of which will be indicated in the claims.

For a fuller understanding of the nature 25 and objects of the invention, reference should be had to the following detailed description taken in connection with the accompanying drawing, in which:

Figure 1 is a perspective view of a sales- 30 book embodying this invention.

Fig. 2 is a modification thereof, showing 35 a different attachment of the auxiliary leaves.

Fig. 3 is a view of a modification similar 40 to that of Fig. 2 but carrying tissues by which a septuplicate record may be made.

In salesbooks having a plurality of leaves bound into a pad, it is desirable for many 45 purposes to insert transfer sheets between the leaves and to retain said sheets in permanent position convenient for such insertion.

In accordance with this invention, the transfer sheet is so mounted that its normal 50 resiliency causes it to extend in the direction of the record sheets so that it may be interleaved between them without folding. In the embodiment of the invention illustrated in Fig. 1, the book comprises a plurality of record leaves as, for example, an original 1, a duplicate 2, and a triplicate 3. As 55 illustrated the triplicates 3 of the successive sets of leaves extend beyond the other leaves to be bound together in a stub

4 by staples 5 and the originals and duplicates 1 and 2 consist of a single sheet folded upon itself as at 6 and detachably attached to the triplicate sheet 3 at 7 at a point free from the stub 4.

The form of book above described is an 60 embodiment of an invention claimed in my co-pending application Serial Number 608,620, filed December 23, 1922.

The salesbook is provided with a backing 65 extending as at 9, beyond the record sheets 1 and 2 and the main portion of the sheets 3 along one edge, as for example, the edge opposite the stub 4. Each of the bound record sheets 3, is provided with an extension 10 which is detachably attached thereto. These extensions 10 are built up into a stub 11 to a height commensurate with the thickness of the salesbook and in this stub 70 there are fastened transfer sheets 12 and 13 which thus extend in the direction of and 75 are adapted to be interleaved between the record sheets. By reason of the fact that the transfer sheets are supported substantially at the height at which they will be used and that they normally extend in the 80 direction in which they will be used, it will be clear that they may be manipulated with a minimum of folding and without the difficulties resulting therefrom.

Should it be desired to provide an additional set of transfer sheets for use with the record sheets of the latter portion of the book, another set of transfer sheets 14 and 15 may be bound at a suitable intermediate 90 portion of the stub and each of these intermediate transfer sheets may be protected by suitable protective tissue sheets 16—17, which may also be bound within the stub.

In the form illustrated in Fig. 2, detachable sheets 21 and 22 of each set are attached 95 to the bound sheet 23 at the lower end as shown at 24, instead of at the top end as in the form first illustrated. In this modification therefore, the carbon sheet 25 may be bound within the stub 26 corresponding to 100 the stub 4 of the form first illustrated, while the other carbon 27 may be bound within the auxiliary stub 28. This form of the invention is convenient to manipulate by reason of the fact that the detachable sheets are 105 attached to the bound sheets near the point 29 at which the bound sheets are attached to the auxiliary stub. In this manner the

detachable sheets serve as a handle for the breaking of the bound sheet from the auxiliary stub.

In either of the modifications illustrated, auxiliary tissue sheets may be provided on any or all of the record sheets in order to provide a greater number of copies of the sales record.

In Fig. 3, such a modification is illustrated in connection with the book of Fig. 2. There are thus provided additional tissues 30, 21, 32 and 33. Sheets 30 and 31 are attached to the under and upper sides respectively of the first and second record sheets, near the upper end, that is, near the fold, while sheets 32 and 33 are attached to the under and upper faces respectively of the second and third record sheets near the lower end.

For the purpose of transferring the inscription on these sheets, an additional or third transfer sheet 34 comprising a piece of double-faced carbon, may be bound within the auxiliary stub in position to lie between the sheets 30 and 31 and a fourth transfer sheet 35 also comprising a piece of double-faced carbon may be bound within the permanent stub to lie between the sheets 32 and 33.

Since certain changes may be made in the above device and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

Having described my invention, what I claim as new and desire to secure by Letters Patent, is:

1. A salesbook comprising, in combina-

tion, plurality of sheets attached together and to a back to form a stub, each of said sheets having a detachable extension on a side other than that toward the stub, said detachable extensions being bound together to form a dummy stub, and carbon sheets interleaved between said first mentioned sheets projecting into and bound within said dummy, but free from said first mentioned stub.

2. A salesbook comprising, in combination, a plurality of leaves being bound together and to a back to form a stub, each of said leaves having an extension on the side opposite said stub, said extensions being bound together into said back to form a dummy stub, and carbon sheets bound within said dummy stub positioned to be interleaved between said first mentioned leaves, said carbon sheets terminating short of said first mentioned stub.

3. A salesbook comprising, in combination, a plurality of leaves bound together and to a back to form a stub, each of said leaves having a detachable extension, said detachable extensions being attached together to form an auxiliary stub, a plurality of auxiliary record sheets attached to each of said bound record sheets and a carbon sheet bound within said auxiliary stub in position to lie between said record sheets.

4. A salesbook comprising, in combination, a plurality of leaves arranged in sets, each set comprising a plurality of leaves attached together, one of said leaves having an extension beyond the attachment in a direction opposite to the remaining leaves, by which said sets are bound together to form a book, a support for said book extending beyond said leaves in a direction opposite to said first mentioned extensions and carbon sheets attached to said support, normally lying in a direction extending toward and lying in a position adapted to be placed between the leaves of said book.

In testimony whereof I affix my signature.

ARTHUR H. PHILLIPS.
